J. J. FRANK.
OIL FILLED LEAD BUSHING.
APPLICATION FILED OCT. 30, 1916.

1,304,469.

Patented May 20, 1919.

Inventor:
John J. Frank,
by Alfred S. Davis
His Attorney

UNITED STATES PATENT OFFICE.

JOHN J. FRANK, OF PITTSFIELD, MASSACHUSETTS, ASSIGNOR TO GENERAL ELECTRIC COMPANY, A CORPORATION OF NEW YORK.

OIL-FILLED LEAD-BUSHING.

1.304.469.

Specification of Letters Patent. Patented May 20, 1919.

Application filed October 30, 1916. Serial No. 128,428.

To all whom it may concern:

Be it known that I, JOHN J. FRANK, a citizen of the United States, residing at Pittsfield, in the county of Berkshire, State of Massachusetts, have invented certain new and useful Improvements in Oil-Filled Lead-Bushings, of which the following is a specification.

My invention relates particularly to an improved mode of securing large oil or compound filled lead bushings to walls, like the casings inclosing electrical apparatus such as transformers, oil switches and the like.

Heretofore large high tension bushings of the type I have improved have been built up of various porcelain members, either separate or cemented together, and secured by iron or metal rods running through clamping members placed above and below the porcelain members. Bushings, when so built up and subject to widely changing temperatures as occur when intermittent or fluctuating loads are carried by the electric apparatus, are subject to severe internal strains due to the differential expansion of the metal and porcelain. In consequence of these strains, the abutting porcelain members develop leaks and occasionally give way.

My improved mode of securing oil filled lead bushings avoids these destructive strains altogether because I employ a securing collar attached to the bushing in such a manner that it becomes substantially an integral part thereof.

For a more exact understanding of my invention and the details thereof, reference may be had to the annexed drawing in which Figure 1 shows, in elevation, a large oil filled bushing embodying my invention, while Fig. 2 is a larger detail view thereof, parts being broken or cut away.

Referring now particularly to Fig. 1, 5 denotes the top wall of a transformer casing to which my improved bushing is bolted by means of the flanged member 6. My bushing consists of two porcelain insulating members 7 and 8 spaced apart by and secured to the iron or metal sleeve 9, of which sleeve the flanged member 6 may be and is here shown as an integral part.

In order to secure the insulating members 7 and 8 to the sleeve 9 in an oil-tight manner, I secure clamping rings 10 rigidly to the members 7 and 8 respectively, in any desired

manner, but preferably by cement 11, as 55 shown in Fig. 2.

The ring 10 is secured to the flange 6 by means of bolts 12, the gasket or packing 13 being inserted so as to make an oil-tight joint. 60

To the upper end of the insulating member 7 is secured the clamping ring 14 in substantially the same manner as clamping ring 10. To ring 14 the cap 16 is secured by means of bolts 15, and upon the cap is secured the glass or other transparent housing 17 above which is secured the capping member 18 in which the leading-in conductor 19 is secured in any convenient and approved manner. 70

The lower insulating member 8 is secured to sleeve 9 in substantially the same manner as is member 7 and is closed at its lower end by cap 20.

It will thus be seen that I have built up 75 an insulating bushing in which the metal and porcelain parts are secured together in such a manner as to be free from internal strains and at the same time provide oil-tight joints so that the bushing as a whole 80 may be filled with oil or other insulating compound, without fear of leakage.

The glass housing 17 is adapted to serve as a gage glass to indicate whether the bushing contains sufficient oil or compound. 85

The flange 6 provides convenient means for clamping the bushing to the cover 5 of a transformer or other electrical apparatus by means of bolts 21 without subjecting the bushing to internal strains. A gasket or 90 other packing 22 may be provided, if desired, to insure an oil-tight joint between the cover and flange 6.

Large bushings such as I have disclosed are customarily provided with fibrous partitions 23 to insure a proper distribution of the oil filling or other insulating compound. Their use, however, comprises no part of my invention and may be entirely dispensed with. 95

While I have described in detail the best means at present known to me for carrying out an embodiment of my invention, I would have it understood that I do not mean to be limited thereby in the choice of mechanical 100 equivalents and the embodiment of means to an end except as defined in the following claims. 105

What I claim as new and desire to secure by Letters Patent of the United States, is:—

1. The combination with insulating members, of a sleeve for spacing said members apart, clamping rings rigidly affixed to said members, and means for securing said rings to said sleeve in an oil-tight manner.
2. The combination with a casing, of insulating members, a sleeve provided with a flange, said sleeve being adapted to space said members apart, said members having clamping rings rigidly affixed thereto and securing means for attaching said rings to said sleeve, and additional securing means for attaching said flange to said casing, all in an oil-tight manner.
3. An oil or compound filled lead bushing comprising the combination with two insulating members having clamping rings rigidly affixed to their two ends, of a spacing sleeve, means for securing said rings to said sleeve and caps adapted to receive a conductor secured to the outer ends of said insulating members.
4. An oil filled type lead bushing com-

prising the combination with two insulating members having clamping rings cemented to their two ends, of a spacing sleeve provided with a flange, to the ends of which the insulating members are secured in an oil-tight manner, and caps adapted to receive a conductor secured in an oil-tight manner to the outer ends of said insulating members.

5. The combination with a casing, of a sleeve having a flange adapted to be bolted to said casing, an insulating member, a clamping ring rigidly affixed thereto adapted to be bolted to said flange, and packing members adapted to secure said ring and flange to said casing in an oil-tight manner.

6. The combination with a casing, of a member secured thereto, a corrugated insulating member and a clamping member rigidly affixed to said insulating member; said clamping member being provided with means for securing it to said first named member.

In witness whereof, I have hereunto set my hand this 26th day of October, 1916.

JOHN J. FRANK.
